C. H. GILL,
MULTIPLE SOUND RECORD TABLET,
APPLICATION FILED DEC. 10, 1919.

Patented Aug. 29, 1922.

UNITED STATES PATENT OFFICE.

CHARLES H. GILL, OF CHICAGO, ILLINOIS.

MULTIPLE SOUND-RECORD TABLET.

1,427,373.

Specification of Letters Patent. Patented Aug. 29, 1922.

Application filed December 10, 1919. Serial No. 343,945.

To all whom it may concern:

Be it known that I, CHARLES H. GILL, a citizen of the United States, residing at Chicago, in the county of Cook and State of Illinois, have invented a new and useful 5 Multiple Sound-Record Tablet, of which the following is a specification.

My invention relates to sound record tablets of the flat and circular or disk type and 10 adapted to have records of sound waves made upon them in such manner as to permit of reproducing said sound waves from said tablets with the aid of a sound reproducing machine, and it relates more specifically to tablets of the type referred to above 15 whereon sound records are carried upon each of its opposite faces.

The objects of my improvement are, first, to provide means for securing together two 20 thin sound record tablets, having sound records upon one side of each, with the record carrying sides of each tablet outwards; second, to provide a strengthening plate between the two thin tablets aforesaid, with 25 means for securing the said tablets to opposite sides of the said plate and for removing and changing said tablets at will; third, to provide means for protecting said tablets from breakage by preventing their direct 30 contact with any surface they might fall upon; and, fourth, to provide means for carrying the reproducing stylus out of contact with the sound record upon said tablets during the first several rotations of said 35 tablets, while the said tablets are accumulating speed, and to bring about operative contact between said stylus and said sound records after a predetermined number of rotations of said tablets.

40 The particular advantages claimed for my invention are that it will allow of the selection by the purchaser of the specific sound records upon each side of the double faced records or tablets instead of having 45 to select the particular record wanted and take whatever may have been put upon the opposite side by the manufacturers; also the protection against breakage and warping of the tablets which it affords and the advantage of allowing the tablet to attain full 50 rotational speed before contacting with the reproducing stylus.

I attain the objects set forth above by the construction set forth in the accompanying 55 drawing, in which—

Figure 1 is a plan view of my multiple

sound record tablet; Figure 2 is a section taken through the center of Figure 1; Figure 3 is an enlarged fragmentary section taken on the line 3—3 of Figure 1; Figure 4 is an enlarged fragmentary plan view of a part of Figure 1; and Figure 5 is an enlarged cross section of the central part of the multiple sound record tablet, illustrating an alternative construction. 60 65

Similar numbers refer to similar parts throughout the several views.

Two very thin disks 11, of the usual record tablet composition or other suitable material, each carry upon their surface a helical record groove 12. A supporting and stiffening plate 13, of metal or other material, is of circular shape and of somewhat greater diameter than the record disks 11, 70 so that the outer edge 14 of the plate 13 extends somewhat beyond the outer edges 15 of the record disks 11 when the said record disks are centered upon the plate 13. The plate 13 and the record disks 11 are each provided with small circular openings 16 extending through their centers. These openings are designated as 16 in the plate 13 and as 17 in the record disks 11. The openings 16 and 17 are either of like diameter or the opening 16 is of somewhat greater diameter than the openings 17. 75 80 85

Rings 18 and 19 are preferably made of metal and are somewhat greater in outside diameter than the plate 13 and somewhat less in inside diameter than the diameters 90 of the record disks 11. The rings 18 and 19 are relatively thick at their outer edges and taper to thinness at their inner edges 20. The said rings are further constructed with shoulders 24 of height corresponding to the 95 thickness of the record disks 11 and adapted to fit around the outer edges 15 of said record disks; also with shoulders 25 adapted to fit over the outer edge 14 of the plate 13. The inner edges 20 of the rings 18 and 19 100 overlap the record disks 11. 105

Screws 21 pass through circular and internally threaded openings 22 in the rings 18 and 19 and through similarly internally threaded openings 23 in the plate 13, all beyond the outer edges of the record disks 11.

The two record disks 11 are selected by the purchaser and are then clamped to the plate 13 by means of the rings 18 and 19 110 and the screws 21. To accomplish this, the ring 19 is laid flat with its shoulders upper-

most. One of the record disks 11 is then laid inside the shoulder 24 and with its record face downwards. The plate 13 is then laid upon the record disk 11 and within the 5 shoulder 25 of the ring 19. The other record disk 11 is now laid upon the plate 13 with its record face upwards and the ring 18 is fitted over it so that the shoulder 24 of the ring 18 fits around the outer edge 15 10 of the record disk 11 and the shoulder 25 fits around the outer edge 14 of the plate 13. The ring 18 is then turned until its threaded openings 22 are in alignment with the threaded openings 23 in the plate 13 and 15 with the threaded openings 22 in the ring 19. The screws 21 are now screwed through the two rings 18 and 19 and the plate 13 and so tightened as to hold the record disks 11 securely. The heads of the screws 21 fit 20 into countersunk depressions in the ring 18.

Two or more convolutions of a helical groove 26 are provided in the surfaces of the rings 18 and 19 near their inner edges 20. These helical grooves 26 run off of the 25 rings 18 and 19 at their inner terminations.

After having been clamped together my multiple sound record tablet may be used upon a sound reproducing machine exactly the same as any other double faced record 30 tablet. When it is desired to also employ the stylus carrying feature, the stylus needle is placed in the outer convolution of the helical groove 26 in the ring 18 or 19 while the machine is at rest. When the rotation 35 of the table carrying the record tablet is started, the stylus needle will follow the groove 26 during the first few rotations, while normal playing speed is being attained, and will run off onto the record 40 grooves in the record disk when it reaches the termination of the groove 26.

An alternative method of clamping the two record disks and the plate 13 together is illustrated in Figure 5. A supporting and stiffening plate 13 carries the record disks 11, these being retained in position upon the plate 13 by means of disks 27. The central portions of the record disks 11 are countersunk to permit the disks 27 to lie 50 flush with the balance of the surfaces of the record disks 11 and the central holes in the record disks 11 are somewhat larger than usual. The disks 27 are provided with circular collars 28 carrying screw threads upon 55 their outer surfaces and these collars are adapted to screw into an internally threaded central opening 29 in the plate 13. The in-

side of the collars 28 constitute an opening of the usual size for receiving the centering pin of the table of the sound reproducing 60 machine.

It will be evident that numerous other means might be employed to accomplish the purposes of this invention. I do not, therefore, limit my invention to the constructions described, its limitations being only those of the following claims.

I claim:

1. In a multiple sound record tablet, the combination of two separate record carrying disks, a central disk, two rings having edges adapted to overlap the edges of said record carrying disks and means for clamping said rings together to secure one of said record carrying disks upon each side of the 75 said central disk.

2. In a multiple sound record tablet, the combination of a central supporting disk, a central and internally threaded opening through said supporting disk, two separate 80 record carrying disks provided with central openings through them, circular depressions in said record carrying disks surrounding said openings through said disks, circular plates adapted to fit into said depressions 85 and threaded collars upon each of said plates adapted to secure one of said record carrying disks upon each side of the said central supporting disk.

3. In a multiple sound record tablet, the 90 combination of two separate record carrying disks of such thinness as to be impractical for ordinary usage without reinforcement, a supporting disk of relatively strong construction and of such greater diameter than 95 the said record carrying disks as to protect the edges of said record carrying disks and means for securing one of said record carrying disks to each side of the said supporting disk.

4. In a multiple sound record tablet, the combination of a supporting disk, record carrying disks adapted to be secured to each side of said supporting disk, two rings having edges adapted to overlap the edges of 105 the said record carrying disks and shoulders adapted to fit around the edges of said record carrying disks and means for securing said rings together and to the said supporting disk and to centrally secure one of 110 said record carrying disks upon each side of said supporting disk.

CHARLES H. GILL.
